UNITED STATES PATENT OFFICE.

KATHERINE V. HOGAN, OF CHICAGO, ILLINOIS.

BUNGALOW-APRON.

1,251,524.

Specification of Letters Patent. Patented Jan. 1, 1918.

Application filed January 29, 1917. Serial No. 145,266.

To all whom it may concern:

Be it known that I, KATHERINE V. HOGAN, a citizen of the United States, residing at Chicago, in the county of Cook and State 5 of Illinois, have invented certain new and useful Improvements in Bungalow-Aprons; and I do declare the following to be a full, clear, and exact description of the invention, such as will enable others skilled in the art 10 to which it appertains to make and use the same.

This invention relates to garments and more particularly to the type of aprons known as bungalow aprons.

15 The object of the invention is to so construct an apron of this character that it may be cut from a minimum quantity of material and yet be of full width and length and of attractive appearance.

20 This object is accomplished by forming the apron in nine pieces, two shoulder pieces being cut additional to the pieces ordinarily cut in making an apron of this kind.

25 With the foregoing and other objects in view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figures 1 and 1^a represent a plan view of a yard wide strip of fabric showing two aprons to be cut, laid out thereon,

Fig. 2 is a plan view of an apron complete except for the sewing up of the side seams;

40 Fig. 3 is a rear elevation after sewing all parts; and,

Fig. 4 is a perspective view applied.

The apron embodying this invention is composed of a front skirt section 1 and two 45 rear skirt sections 2 and 3. Each section is formed of a single piece of material and the sections 2 and 3 are seamed at their outer edges to the edges of section 1 to form a skirt. All of the sections 1, 2 and 3 50 are of greater width at their lower than at their upper ends and this economizes in material as will be hereinafter explained. The front section 1 preferably has a central protuberance 4 at its upper end midway be- 55 tween its side edges from which protuber-

ance said upper end slopes downwardly toward said side edges and is preferably curved inwardly as shown at 5.

The body-encompassing portion of the garment is formed from a central member 6 60 in the form of a substantially rectangular piece of material and two shoulder strips 7 which are seamed along their inner side edges to the side edges of the central member 6. The outer side edges of these strips 65 7 are curved at their ends as shown at 8 and the curved edges of each section 7 are designed to be seamed together to close the body and form the arm holes in which are secured the sleeves 10. The portions 8 of 70 the edges of the strips 7 are flush with the outer edges of the skirt sections 1, 2 and 3 so that only one vertical seam is necessary on each side of the garment.

The central body member 6 has a portion 75 11 cut out to form the neck opening 12 and this cut out portion 11 is utilized to make a patch pocket.

A belt 13 is stitched at one end in the side seam which unites the curved portions 80 8 of the edges of the shoulder strips 7 and the other end of said belt is designed to be detachably secured at the other side of the garment by a button and buttonhole or similar fastening means. 85

When the apron is so constructed, one front skirt section 1 and two shoulder strips or sections 7 may be cut from a single width of fabric as is shown clearly in Fig. 1, and from another width of the fabric adjacent 90 that from which the skirt and shoulder sections are cut may be cut the two rear skirt sections 2 and 3, the two sleeve members 10 and the belt 13, the belt being cut off from the portion of goods which is arranged between the sloping sides of the back sections and the sleeve members 10. From the next length of fabric may be cut the front skirt section 1 and the shoulder sections 7 of another apron and from the adjacent width 100 of fabric the two back skirt sections and the sleeve sections of another apron may be cut, also the belt of one of the aprons, and from the remaining portion of the fabric is cut the two body portions and the pockets of the 105 two aprons, the pockets 11 being formed from the portions cut out at the neck of the body portion. The neck is substantially U-shaped and cut out along the line 14, while the pockets are preferably made angular as 110

shown, although they need not necessarily be so made, but may be of any other desired configuration.

It will thus be seen that by constructing 5 the body of the apron of a central section or member with two shoulder strips 7 seamed thereto along the side edges, every available part of the fabric strip may be utilized, the shoulder strips 7 being cut out 10 at either side of the strip of goods beyond the side edges of the front skirt section. If the shoulder strips 7 were not employed, considerable more material would be necessary for cutting out an apron which is 15 otherwise shaped the same as the one above described, the principal difference in the improved apron from those ordinarily made being that the body-encompassing portion is formed of a central member 6 and two shoulder strips 7 seamed together, while in the 20 ordinary apron, the body portion is made in one piece with sleeves or cuffs secured thereto.

The apron above described may be made 25 in any style desired, that is, buttoned either front or back and the sizes may vary as required. To render the apron more attractive, the seams which connect the shoulder sections with the central body section and 30 those which connect the front skirt section with the body section may be piped, although not necessarily so and when they are piped, the edges around the neck and sleeves

and the edges of the belt are preferably bound with a similar material to that from 35 which the piping is made. The seam uniting the sleeves 10 to the shoulder sections is also preferably piped as shown.

I claim:—

An apron comprising a skirt formed of 40 front and rear sections seamed together at their side edges and a separate body-encompassing portion seamed to the top of said skirt, said body being formed of a one-piece central member having its side edges spaced 45 inwardly from the side edges of said front and rear sections and having a neck opening therein, said skirt and body portion having an opening extending from the neck opening down through the lower end of the 50 skirt, shoulder strips united along their inner edges to said side edges of said central member, the outer edges of said shoulder sections being flush with the side edges of said front and rear sections and shaped to 55 form armholes with curved side seams below the arm holes, and sleeves seamed to the edges of said arm holes.

In testimony whereof I have hereunto set 60 my hand in presence of two subscribing witnesses.

KATHERINE V. HOGAN.
